CLAIM

The ornamental design for a liquid chamber, as shown and described.

DESCRIPTION

FIG. 1 is a front, right side and top perspective view of a first embodiment of the liquid chamber, which embodies my design.

FIG. 2 is a rear, left side, and top perspective view thereof.

FIG. 3 is a front view thereof.

FIG. 4 is a rear view thereof.

FIG. 5 is a right side view thereof.

FIG. 6 is a left side view thereof.

FIG. 7 is a top view thereof.

FIG. 8 is a bottom view thereof.

FIG. 9 is a front, right side, and top perspective view of a second embodiment of the liquid chamber, which embodies my design.

FIG. 10 is a rear, left side, and top perspective view thereof.

FIG. 11 is a front view thereof.

FIG. 12 is a rear view thereof.

FIG. 13 is a right side view thereof.

FIG. 14 is a left side view thereof.

FIG. 15 is a top view thereof.

FIG. 16 is a bottom view thereof; and,

FIG. 17 is a right side exploded view thereof.

The broken lines in the drawings depict portions of the liquid chamber that form no part of the claimed design.
